* cited by examiner

Primary Examiner — Mark Goodwin(74) *Attorney, Agent, or Firm* — Antonelli, Terry, Stout & Kraus, LLP.(57) **CLAIM**

We claim the ornamental design for a portion of a hydraulic excavator, as shown and described.

DESCRIPTION

FIG. 1 is a partially enlarged perspective view of a portion of a hydraulic excavator showing our new design;

FIG. 2 is a rear elevational view showing by solid lines the portion of a hydraulic excavator;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front elevational view thereof.

The broken lines shown are for illustrative purpose and form no part of the claimed design.
